(57) **CLAIM**

The ornamental design for a laboratory apparatus, as shown and described.

DESCRIPTION

FIG. 1 is a perspective view of the laboratory apparatus. FIG. 2 is a front plan view of the laboratory apparatus. FIG. 3 is a back plan view of the laboratory apparatus. FIG. 4 is a left side view of the laboratory apparatus. FIG. 5 is a right side view of the laboratory apparatus. FIG. 6 is a top plan view of the laboratory apparatus; and, FIG. 7 is a bottom plan view of the laboratory apparatus. A laboratory apparatus for investigation of samples, e.g. by optical detection or imaging, analytical measurements or the like.
